TEXTILE APPARATUS

Charles Wesley Addy, Reginald Henry John Eiley, and Reginald John Grinnell, Spondon, near Derby, England, assignors to Celanese Corporation of America, a corporation of Delaware

Application December 2, 1936, Serial No. 113,782
In Great Britain December 24, 1935

7 Claims.

(Cl. 18—8)

This invention relates to improved textile apparatus and particularly to apparatus for the delivery or winding of threads of artificial filaments continuously with their manufacture by extrusion. The invention is particularly concerned with processes for delivering or winding such threads in which a feed roller is employed to draw the thread from a source of supply, e. g. spinning jet, and deliver it to some points of use, e. g. a winding or twisting and winding device.

Where, as in the dry spinning of artificial threads, the feed roller serves to draw the thread of filaments continuously and deliver it to a winding or twisting and winding device, occasions occur in which the feed roller serves as a recipient for the thread while winding is interrupted. Thus, during the starting up of the winding operation or during bobbin changing, waste thread is collected on the feed roller to be removed after winding has been commenced or recommenced. For example, in starting up spinning the thread of filaments that has descended the cell is drawn from the cell and applied to the feed roller and is there collected until it can be carried to the bobbin on which it is wound. Then again, when the bobbin is completed, the thread end is broken between the feed roller and the bobbin and continues to be collected by the feed roller until the full bobbin has been replaced by the empty bobbin. The transfer of the thread to the bobbin is effected by separating the end of thread proceeding from the cell from the ring of waste that has collected on the roller, and the thread is left passing about once round the feed roller (usually being threaded through a back guide at the rear of the roller) and thence to the bobbin. The ring of waste thread has then to be removed from the roller.

The ordinary method of removing the waste is to slide it along the feed roller to a waste roller of lesser diameter that is not secured to the feed roller shaft. The operative's hand is inserted in the ring of waste and the waste roller is brought to rest by pulling on the waste to enable the ring to be cut through and completely removed.

According to the invention, there is provided adjacent the end of the feed roller a waste support which is held stationary. By this means, when the waste is slid from the feed roller on to the support there is no danger of snatch being applied by the support to the ring of waste, and the ring can easily be cut away for removal, whereas in the old arrangement, if the waste

roller was not sufficiently free of the feed roller shaft to be easily brought to rest, it was possible that snatch might be applied to the ring of waste when seized by the operative, with consequent danger to the fingers of the operative.

The stationary support may be mounted in any convenient manner, and even completely independently of the feed roller and the feed roller shaft. It is, however, convenient to mount the support on or round the feed roller shaft and to hold the support stationary by means such as a rod or arm connecting the support to some convenient part of the machine. Thus, an arm may be connected to the support so as to extend rearwardly, rearwardly and downwardly, or rearwardly and upwardly from the support to the frame so as to leave the top and front portions of the support clear for the cutting of the ring of waste.

Where the waste support is mounted on the feed roller shaft, it may have a plain journal bearing directly on the feed roller or may be provided with roller or ball bearings. Provision should be made for lubrication of the support on the shaft.

The waste support is conveniently of capstan shape or waisted, so that when the waste is seized by the operative it is drawn away from the end of the feed roller.

In order to ensure the easy transfer of waste to the support, the feed roller should preferably overlap the support, and the overlapping end of the feed roller may also be chamfered. It is also advantageous to arrange that the portion of the feed roller on which the yarn is received is somewhat tapered so that only a slight end-wise movement with a knife or other tool is necessary to free the ring of waste and enable it to be slid easily to the end of the roller. This tapering should be slight in extent so as to interfere as little as possible with the denier of the thread, which is, of course, determined by the peripheral speed of the part of the roller engaged by the thread, and guides should be arranged so as to direct the thread to a definite part of the tapered portion having a predetermined peripheral speed.

The apparatus according to the invention may be employed with any suitable winding device, cap- or ring-spinning devices being suitable where it is desired to twist the thread. The thread may be wound on to packages of any desired type, e. g. parallel wound flanged bobbins; bobbins with different-sized flanges to receive thread so traversed as to leave all or part

of the surface of the package tapering down to the smaller flange; parallel, tapered, or partly tapered tubes or other supports to receive thread traversed with a cop- or bottle-bobbin wind; or 5 tubular supports to receive the thread traversed over the whole length of the package into a cop-like shape as described in U. S. application S. No. 92,966 filed July 28, 1936.

The accompanying drawing illustrates the invention,¹⁰

Figs. 1 and 2 showing transverse sections through a bank of spinning cells, feed rollers and a cap spinning frame, and

Fig. 3 a longitudinal view partly in section of 15 an arrangement of feed rollers and waste supports in accordance with the invention.

The sectional view in Figs. 1 and 2 of the feed roller and waste support apparatus is taken on the line 4—4 of Fig. 3.

20 Referring to Figs. 1 and 2, the artificial silk filaments 5 from a bank of spinning cells 6 are carried round the feed rollers 7 through the back guide 8, thence over the top of the feed rollers to the balloon guide 9 of a cap-spinning device 25 10. The threads are lubricated at any suitable point on their way to the cap-spinning device.

Referring to Fig. 3, the feed rollers 7, each designed to deliver two threads, are provided at each end with slightly tapered portions 11 and 30 chamfered edges 12, and are mounted on a shaft 13 passing through bosses 14 and being secured to the shaft by set screws 15. The shaft is carried at its ends or at intervals in bearings 16. Alternating with the feed rollers 7 are stationary 35 waste supports 17 waisted as shown and secured to the frame by brackets 18. As shown in Fig. 3, the ends of the feed rollers 7 overlap the waste supports 17. The threads by means of suitable 40 guides are run on the tapered portions 11 of the feed rollers 7. This tapering of the feed rollers assists removal of waste therefrom, and this removal is further assisted by the chamfered ends 12. When the operative has brought the ring of waste on to the waste support 17 and pulls 45 on the ring so as to cut it through, there is no danger of snatch since the waste support 17 is stationary.

Instead of providing a single feed roller for each pair of threads, obviously a single feed roller 50 may be provided for each thread. A feed roller for a single thread is illustrated at each end of the drawing in Fig. 3. In such an arrangement using a feed roller for each individual thread, the stationary waste supports may alternate with each feed roller or with each pair of feed rollers.

Having described our invention, what we desire to secure by Letters Patent is:

1. Apparatus for delivering threads, comprising a source of supply of the thread, a rotatable shaft, 60 a feed roller secured to said shaft and a stationary tubular waste support having one diameter smaller than the diameter of the feed roller,

which support is disposed about said shaft adjacent the end of the feed roller so that waste can be slid from the feed roller on to the support.

2. Apparatus for delivering threads, comprising a source of supply of the thread, a device for winding and twisting the thread, a rotatable shaft, a feed roller secured to said shaft and adapted to forward the thread to the winding and twisting device and a stationary tubular waste support having one diameter smaller than the diameter of the feed roller, which support is disposed about said shaft adjacent the end of the feed roller so that waste can be slid from the feed roller on to the support. 5

3. Apparatus according to claim 1, wherein the tubular waste support is formed with a waist. 10

4. Apparatus for delivering threads, comprising a source of supply of the thread, a rotatable shaft, a feed roller secured to said shaft, said feed roller being formed with a slightly tapered thread carrying portion, a thread guide adapted to guide the thread on to and maintain it on said tapering portion and a stationary tubular waste support having one diameter smaller than the diameter of the feed roller, which support is disposed about said shaft adjacent the end of the feed roller so that waste can be slid from the feed roller on to the support. 20 25

5. Apparatus for the manufacture of artificial threads, which comprises a spinning unit delivering an artificial thread, a rotatable shaft, a feed roller secured to said shaft and feeding a thread, and a stationary tubular waste support having one diameter smaller than the diameter of the feed roller, which support is disposed about said shaft adjacent the end of the feed roller so that waste can be slid from the feed roller on to the support. 30 35

6. Apparatus for the manufacture of artificial threads, which comprises a number of spinning units each delivering a single artificial thread, a rotatable shaft, a series of feed rollers secured to said shaft and each feeding two threads, stationary tubular waste supports each having one diameter smaller than the diameter of the feed rollers and each disposed about said shaft and between and adjacent the ends of two adjacent feed rollers, so that waste can be slid from the feed rollers on to the supports. 40 45

7. Apparatus for delivering threads, comprising a source of supply of the thread, a rotatable shaft, a feed roller secured to said shaft and, adjacent the end of the feed roller, a fixed tubular waste support disposed about said shaft, an end of the feed roller being provided with a rim over-lapping an end of said waste support to facilitate the transference of waste from the feed roller to the support. 50 55
